United States Patent Office.

HENRY. CARNEGIE CARDEN, OF PARIS, FRANCE

Letters Patent No. 65,542, dated June 11, 1867.

IMPROVEMENT IN METRONOMES.

The Schedule referred to in these Letters Patent and making part of the same.

TO ALL WHOM IT MAY CONCERN:

Be it known that I, HENRY CARNEGIE CARDEN, of Paris, in the Empire of France, have invented "a new and useful improvement in the construction of Metronomes, or apparatus for measuring intervals of time;" and I do hereby declare that the following is a full, clear, and exact description thereof, reference being had to the figures of the annexed drawing, making part of this specification, that is to say—

My invention consists in a novel combination of mechanism applied to the construction of the instruments known as "metronomes," or apparatus for measuring intervals of time, and especially intended to mark at will, in music, the time of those notes only which are naturally accentuated.

Figure 1, of the accompanying drawings, is a front view of the mechanism.

Figure 2 is a vertical section of the same, (side view.)

Figure 3 represents the indicator plate.

In all these figures similar parts of the mechanism are indicated by the same letters of reference. *a a a* are two plates enclosing the different parts of the apparatus, and separated from each other by the pillars *b b b*. *c* is the suspension-plate of the pendulum-rod. *d* is a double or anchor-shaped lever, similar to that used in certain kinds of clocks. *e* is the escapement-wheel carrying eighteen teeth. *f* is a ratchet-wheel with nine teeth and nine spaces, mounted parallel to the wheel *e*, the required separation between the two faces being maintained by the pillars *g g*, by which both wheels are connected together. *h h* is an intermediate wheel cogging with the pinion *i* of the escapement *e*. *j j* is another toothed wheel mounted on the barrel *k k*, in which is coiled the motive spring, as in ordinary time-keepers. This wheel *j j* cogs with the pinion *l* of the intermediate wheel *h*. *m* is the arbor of the barrel-wheel. *n* is the arbor of the anchor *d*. *o o o* are the bearings of the different arbors, formed in the back and front plates of the apparatus. *p p* is the pendulum-rod. *q* is the fork. *r*, suspension of the pendulum-rod. *s*, suspension of the fork *q*. *t* is the arbor of the rocking-lever *u*, the upper or beak-shaped extremity of which acts on the ratchet-wheel *f*, while to the lower extremity is secured a fine thread, *v*. *x*, fig. 3, is a double plate, the parallel surfaces of which are separated by pivot columns to the distance of about one-fifth of an inch. *y* is the indicator, formed of any suitable light material, (such as the barb of a feather,) the stalk of which passes into the spiral spring *z*. The plate *x x*, fig. 3, being placed in any required position, is connected by means of the thread *v* with the foot of the rocking-lever *u* of the main apparatus, figs. 1, 2. The main-spring enclosed in the barrel *k* being wound up, the motion is imparted to the wheels *h*, *f*, and *e*, to the anchor *d*, the pendulum *p*, and the fork *q*. During this movement the rocking-lever *u*, cogging by its upper end on the ratchet-wheel *f*, draws backward and forward the thread *v* attached to its lower extremity, and communicates the required motion to the indicator *y*, which thus marks the time according to the rise and fall of the pendulum. When so desired, a pair of chimes or other sounding mechanism may be applied to the apparatus, and acted on by a cross-bar or other equivalent arrangement attached to the pendulum-rod.

The apparatus constructed as above is, as before stated, especially intended for marking time in music, but it is obvious that by slight modifications in the details of form and arrangement, the same mechanism may be applied to the construction of alarm-clocks and other instruments for the measurement of intervals of time.

Having now described the nature of my said invention, and the manner of carrying it into effect, I declare that what I claim as my improvement in the construction of metronomes, and desire to protect by Letters Patent, is—

The combination of the ratchet-wheel *f*, mounted on an escapement-wheel *e*, with the rocking-lever *u*, the thread *v*, and the spiral spring *z*, in manner and for the purposes substantially as herein set forth and shown in the figures of the annexed drawing.
